MERIAN H. DICKINSON, OF SEATTLE, WASHINGTON, ASSIGNEE TO LIDGERWOOD PACIFIC COMPANY, OF TACOMA, WASHINGTON, A CORPORATION OF WASHINGTON

VARIABLE SPEED SKIDDING DEVICE

Application filed July 11, 1929. Serial No. 377,421.

In skidding logs by what is known as the overhead interlocking cableway system, that is, a system in which the inhaul and skidding drum, and the outhaul or receding drum, are 5 locked together and rotated in unison when bringing in the logs, one of the difficulties present in the system has resulted from the varying effective diameters of the drum carrying the inhaul or skidding cable and 10 that carrying the outhaul or receding cable while in operation. When the log is being dragged or drawn from the tail tower towards the head tower, the cable piles up on the skidding and inhaul drum and increases 15 the effective diameter thereof, and pays out on the outhaul or receding drum with a decrease in its effective diameter and with a corresponding change in the relative effective diameters of the two drums, with the result 20 that there is a tendency for the log to rise and the attaching parts therefor to jam against the carriage.

My invention has for one of its objects the overcoming of the foregoing difficulty, by 25 changing the speeds of both the inhaul and the outhaul drums during the normal operation and thereby providing for a plurality of changes of speed.

Another object of my invention is the provision of means by which the logs can be "broken out" or brought to a position near the tail tower with the skidding drum operating at high power and low speed.

Other objects of my invention will appear 35 in the specification and will be more particularly pointed out in the claims.

My invention will best be understood by reference to the accompanying drawings in which I have illustrated certain embodiments 40 of my invention, and in which Fig. 1 is a diagrammatic view illustrating an overhead cableway system operated by a steam engine and adapted to skid logs to a position underneath the main cable and then bring the logs 45 in from a position near the tail tower towards the head tower; Fig. 2 is a plan view of the skidding engine; Fig. 3 is a diagrammatic side view of a portion of Fig. 2 and illustrating the manner in which the rope piles up 50 or pays out on the respective drums as the log

is brought from a position near the tail tower towards the head tower, and Fig. 4 is a plan view of a modified form of my invention in which the system is operated by an electric motor.

Like reference characters indicate like parts throughout the drawings.

Referring now to the drawings, and first to Fig. 1, 10 is a main cable attached at its ends to a head tower 11 and to a tail tower 12 by means which are well understood in the art. A skidding and inhaul cable 13 passes over a sheave 14 on the head tower and is wound upon a skidding and inhaul drum 15 mounted on the skidding engine 65 which I have indicated generally at A. The other end of the cable 13 passes over a sheave 131 attached to a carriage 16, and is provided at its free end with tongs 132 or other suitable means by which the skidding and inhaul 70 cable may be attached to a log or other device.

The outhaul cable 17 passes over a sheave 18 on the head tower and is wound on the outhaul or receding drum 19. In the embodiment of my invention illustrated, the outhaul cable 75 17 passes over a sheave 171 which is shown attached to a stump, thence over a sheave 172 attached to the tail tower, the free end of the outhaul cable being attached to the carriage 16 as at 173. In the embodiment illustrated, a slack pulling line 20 passes over a sheave 21 and is wound upon a drum 22, the opposite end of the slack pulling cable passing over a sheave on the carriage as indicated in Fig. 1, and is attached to the inhaul cable as at 201.

Referring now particularly to Figs. 2 and 3 of the drawings, 23 is a frame on which are mounted the drums 15 and 19 having their bearings at 24 and 25, respectively, the drums being mounted side by side. The drums 15 and 19 are loosely mounted upon shafts 141 and 191, respectively, and are slideable longitudinally of their respective shafts.

A gear 26 is fast on the shaft 141 at one end of the drum 15, and a gear 27, which meshes with the gear 26, is fast on its shaft 191 at the same end of the drum 19. Meshing gears 28 and 29 are loosely mounted on the shafts 141 and 191, respectively, at the other ends of

the respective drums 15 and 19. The gear 26 is preferably of approximately the same diameter as that of the gear 27 with which it meshes, but is of smaller diameter than the gear 28 at the opposite end of the drum 15. 5 The gear 27 is preferably larger than the gear 29, as illustrated in Fig. 3.

The drum 15 is provided with suitable friction clutch members 142 and 143 which are mounted on the drum 15. When the drum 15 is moved towards the gear 26 as viewed in Fig. 2, the friction member 142 engages a corresponding friction member on the gear 26. Thereby causing the drum to rotate with 10 the gear 26. The details of such friction clutch members are well understood in the art, and I have, therefore, for the sake of simplicity not illustrated such details. Similarly, when the drum 15 is moved in the opposite direction, the friction member 143 on the drum engages the corresponding friction member on the gear 28, thereby causing the drum to rotate with the gear 28. The drum 15 is also provided with friction members 192 15 and 193 which engage the friction members on the gears 27 and 29, respectively, and cause the drum to rotate either with the gear 27 or with the gear 29 in accordance with the direction in which the drum has been moved.

20 The drums are moved longitudinally of their shafts by suitable members 30 which operate by steam or air, suitably controlled by valves, if desired, or they may be manually operated. The driving mechanism for 25 the drums 15 and 19 is here shown as a shaft 31 having its bearings in the frame 23 of the machine, and in turn driven by a steam engine the cylinders of which are illustrated at 32, the connections between the pistons thereof including the piston stems, being illustrated by the dotted line 33. The ends of these connections are attached to crank pins 34 on suitable crank discs 35 secured to the shaft 31.

Secured on the shaft 31 are two pinions 36 40 and 37, the first of which engages the gear 26 and the other of which engages the gear 28. All of the gears 26, 27, 28, and 29, therefore, 45 rotate during the operation of the device. Preferably, the pinion 36 is of larger diameter than the pinion 37. An additional gear 38 is mounted loosely on the shaft 31 and engages a gear 39 which is bolted or otherwise secured to the drum 19. A clutch member 40 is splined on the shaft 31 and is movable longitudinally thereof into frictional engagement with the pinion 38. The clutch is moved longitudinally of the shaft by mechanism incompletely illustrated, but shown somewhat 55 diagrammatically at 41, which causes the pinion 38 to rotate with the clutch member.

60 The slack pulling drum 22 may be operated by a gear 42 meshing with the gear 27, the drum being slidably along its shaft into engagement with the gear and operable by

mechanism not illustrated, as it constitutes no part of my invention.

The operation of the system and of the device embodying my invention, as illustrated in Figs. 1 to 3, will readily be understood 70 from the foregoing description and is as follows:

In order to "break out" or skid the logs from outlying positions in the woods to a position underneath or near the main cableway, 75 the outhaul drum 19 is preferably disconnected from both the gears 27 and 39 and held by the band brake, and the drum 15 is forced into frictional engagement with the gear 28 and is thereby actuated by the pinion 37 of 80 comparatively small diameter and the gear 28, thereby "breaking out" the logs at high power and low speed and bringing them to a position indicated, for example, at (1). When the log is brought adjacent to the main cableway, then by keeping applied the brake on the drum 19 and operating the skidding and inhaul drum 15 in the inhaul direction, 85 the log is lifted from the ground either partially or wholly, and is then ready to be transferred from the position which it then occupies to a position near the head tower or an intermediate position.

When the load is at a position near the tail tower as, for example, at position (1), the cable wound on the skidding drum is practically all paid out, and the diameter of the cable thereon is, therefore, at a minimum as indicated at (1) in Fig. 3, whereas the cable on the 90 outhaul or receding drum is piled up to a maximum extent as also indicated at (1) in Fig. 3. In the embodiment illustrated, however, the diameter of the skidding and inhaul drum 15 is larger than that of the 95 outhaul drum 19. Now by moving the drums 15 and 19 into frictional engagement with the gears 26 and 27, respectively, the load starts from the position near the tail tower towards the head tower. During this movement, the cable piles up on the skidding and inhaul 100 drum to a larger diameter, and pays out on the receding or outhaul drum to a smaller diameter. In order to prevent the load from unduly changing its vertical position, I 105 change the relative speeds of the inhaul and the outhaul drums. For example, when the load has reached the position (2) indicated in Fig. 3, and when the relative diameters of the cable wound on the inhaul and the outhaul 110 drums may be about the same as indicated at (2) in Fig. 3, I force the outhaul drum 19 from frictional engagement with the gear 27 into frictional engagement with the gear 29. The drum 15 which is still rotated by the gear 26 rotates at the same speed, but the drum 19, 115 while it is rotated by the pinion 37 through the gear 28 of somewhat smaller diameter than the pinion 36, the gear ratio is such that the drum 19 is at this time rotated at a higher 120 rate of speed than at position (1). The inter-

125

130

lock between the drums 15 and 19 is thus changed from the gears 26 and 27 to the gears 26 and 29. The changes in speed ratio between the drums 15 and 19 thus counteract any tendency of the load to rise.

When the load is brought in still further, for example to position (3), the drum 19 remains in frictional engagement with the gear 29, and the drum 15 is forced into engagement with the gear 28, thereby causing the drums to be interlocked through the gears 28 and 29. The gear 28 being actuated by the comparatively small pinion 37, thereby further decreases the speed ratio of the drum 15 relatively to the drum 19. When the load reaches the point (4), the speed ratio of the drum 15 relatively to the drum 19 may be still further decreased by retaining the drum 15 in frictional engagement with the gear 28 and moving the drum 19 back into frictional engagement with the gear 27. In other words, the drum 15 will be rotated at the same rate of speed as discussed under position (3), but the drum 19 will be rotated at a higher rate of speed, since it will be rotated through the pinion 36 and the gears 26 and 29.

By the provision of gears at opposite ends of the two drums having different diameters, and the provision of the actuating pinions 36 and 37 having different diameters, I am enabled to change the actual speed of both the skidding drum and inhaul drum, and the out-haul or receding drum during the normal operation, and thereby provide a variety of speeds. At the same time, by providing the pinion 37 of relatively small diameter engaging the gear 28, I am enabled to "break out" or skid the logs to a position adjacent the main cableway at high power and low speed.

The pinion 38 is preferably larger than either of the pinions 36 and 37, and when the carriage is near the head tower, it may be brought at relatively high speed to a position adjacent to the tail tower by disengaging the drum 15 from both the gears 26 and 28 and bringing the clutch on the shaft 31 into frictional engagement with the pinion 38.

In the embodiment of my invention illustrated in Fig. 4, the drums and the gears therefor are substantially the same as those illustrated in Figs. 2 and 3, but the engine is driven by an electric motor 40, and two different speeds are provided for the engine as a whole.

On the motor shaft 41, which has its bearings at 42, is mounted a fixed pinion 43 meshing with a reduction gear 44 mounted on a shaft 45 having its bearings at 46 in the frame of the machine. Also mounted on the shaft 45 are two gears 47 and 48, the gear 47 having a larger diameter than the gear 48, and which mesh with gears 49 and 50, respectively, on a shaft 51 also having its bearings in the frame of the machine. The gear 49 has a smaller diameter than the gear 50. The gear

47 is loose on its shaft, whereas the gear 48 is fixed thereon, while the gear 50 is loose on the shaft 51 and the gear 49 fixed thereon.

A friction clutch member 52 is fixed on the shaft 45, the gear 47 being movable longitudinally of the shaft 45 by the pressure operated device 30, so that the gear 47 may be caused to rotate with the shaft.

A friction clutch member 53 is fixed on the shaft 51, and the gear 50 is movable longitudinally of its shaft by the pressure operated device 30 to bring the same into engagement with the friction member 53 and to cause the gear 50 to rotate the shaft 51.

The gear 49 which engages the gear 26 at the end of the skidding drum 15 may, therefore, be driven at different speeds through the gear 47, or through the gears 48 and 50.

The gear 26 engages the pinion 36 on the shaft 31, and thereby drives said shaft. The gear 26 meshes with the gear 27, and the gear 28 meshes with the gear 29 as in the arrangement illustrated in Fig. 2. Likewise, the pinion 37, having a smaller diameter than the pinion 36, is mounted on the shaft 31 and meshes with the gear 28.

In the embodiment of my invention illustrated in Fig. 4, which illustrates a device which is in use, each of the gears 26 and 27 is provided with 94 gear teeth, the gear 28 is provided with 105 gear teeth, the gear 29 is provided with 83 teeth, while the pinions 36 and 37 are provided with 24 and 18 gear teeth, respectively.

In the arrangement shown in Fig. 4, the same results are obtained as are secured in Fig. 2, but the sequence of operations of the drums are somewhat different and are as follows:

At position (1) of Fig. 1, the drum 15 is forced towards the gear 28 so that it is rotated thereby, the gear 28, in turn, being rotated by the pinion 37. The drum 19 is forced into frictional engagement with the gear 27. The gear ratios between the pinion 37 and the gear 28 is, therefore, 13:105, whereas the gear ratio of the pinion 36 to the gear 26 or 27 is 24:94, which gives a ratio between the two of 1:2.06. In other words, for each revolution of the skidding drum, the receding drum is operated 2.06 revolutions.

At position (2), the drum 15 continues to be rotated by the pinion 37 through the gear 28, whereas the drum 19 is forced towards the gear 29 and is frictionally driven thereby. The gear ratio for the drum 15, therefore, is still 13:105, whereas the gear ratio for the drum 19 is 13:83. In other words, the skidding drum and the receding drum are rotated at the relative speeds 1:1.26.

At position (3), the drums 15 and 19 are forced into frictional engagement with the gears 26 and 27, respectively, and the gear ratio for the drum 15, therefore, is 24:94,

the gear ratio for the drum 19 is 24:94, and the speed ratios for the two drums is 1:1.

At position (4), the drum 15 is retained in frictional engagement with the gear 26, whereas the drum 19 is again forced into frictional engagement with the gear 29, so that, while the gear ratio for the drum 15 is still 24:94, the gear ratio of the drum 19 is 13:83. In other words, the speed of the 10 skidding drum to that of the receding drum is 1.63:1.

It will be noted, furthermore, that both drums may be operated at relatively high power and low speed through the gears 48, 15 50, and 49, or at comparatively low power and high speed through the gears 47 and 49.

I claim:

1. In combination, a main cable, a carriage mounted thereon and adapted to be moved therealong, a driving member, an inhaul and an outhaul drum on which cables are wound, said cables being connected to and adapted to move said carriage in opposite directions, means for driving said inhaul and outhaul drums in interlocked relation in the inhaul direction, and means for changing the speed ratio of said drums while rotating in the inhaul direction by changing the speed of rotation both of said inhaul and of said outhaul drums.

2. In combination, a main cable, a carriage mounted thereon and adapted to be moved therealong, a driving member, an inhaul and an outhaul drum on which cables are wound, 35 said cables being connected to and adapted to move said carriage in opposite directions, means for driving said inhaul and outhaul drums in interlocked relation in the inhaul direction, and means for progressively changing the speed ratio of said drums while rotating in the inhaul direction by changing the speed of rotation both of said inhaul and of said outhaul drums.

3. In combination, a main cable, a carriage mounted thereon and adapted to be moved therealong, a driving member, an inhaul and an outhaul drum and their shafts on which drums cables are wound, said cables being connected to and adapted to move said carriage in opposite directions, means for driving said inhaul and outhaul drums in interlocked relation in the inhaul direction, and means comprising gears mounted at opposite ends of said drums for changing the speed 55 ratio of said drums while rotating in the inhaul direction by changing the speed of rotation both of said inhaul and of said outhaul drums.

4. In combination, a main cable, a carriage mounted thereon and adapted to be moved therealong, an inhaul and an outhaul drum on which cables are wound, said cables being connected to and adapted to move said carriage in opposite directions, means for 65 driving said inhaul and outhaul drums in

interlocked relation in the inhaul direction, and means comprising first gears fast on their shafts at one end of said drums and second gears loose on their shafts and at the other end of said drums and of different diameters 70 from said first gears, both of said drums being longitudinally movable of their respective shafts into operative relation to the gears at either end, and means for driving said gears.

5. In combination, a main cable, a carriage mounted thereon and adapted to be moved therealong, an inhaul and an outhaul drum on which cables are wound, said cables being connected to and adapted to move said carriage in opposite directions, means for driving said inhaul and outhaul drums in interlocked relation in the inhaul direction, 80 means for changing the speed ratio of said drums while rotating in the inhaul direction by changing the speed of rotation both of said inhaul and of said outhaul drums, and a drive shaft provided with pinions of different diameters for actuating the respective gears at the opposite ends of said drums. 90

6. In a winding engine, a rotatable driving member, an inhaul and an outhaul drum, means for driving said drums in interlocked relation in the inhaul direction, and means for changing the speed ratio of said drums when rotating in the inhaul direction by changing the speed of rotation both of the inhaul and of the outhaul drums.

7. In a winding engine, a skidding and inhaul drum and an outhaul drum, shafts on which said drums are mounted, first gears mounted at one end of said drums, second gears mounted at the other end of said drums and loose on their respective shafts, means for moving said drums longitudinally of their shafts into operative relation with said first or second gears, a drive shaft, pinions of different diameters mounted thereon for actuating said first and second gears respectively whereby the skidding and inhaul drum may be operated at low speed and the outhaul drum disengaged from its associated gears for skidding logs at high power and low speed and the speed ratio of said inhaul and outhaul drums may be varied in interlocked position by varying the speed both of the inhaul and of the outhaul drums.

MERIAN H. DICKINSON.
